 Bankers Box Company, Chicago, Ill., a corpora-
 tion of Illinois

Application June 14, 1937, Serial No. 148,038

4 Claims. (Cl. 45-2)

My invention contemplates and provides a novel and advantageous collapsible filing cabinet of the drawer type which may be fabricated very largely of paper board and which, when its several parts are in erected assembly, is very strong, easy to manipulate and of neat and sturdy appearance.

By the term "filing cabinet," as herein used, is meant one or more stacks of drawer-holding cases, employed for day-to-day or transfer filing.

A salient object of the present invention is to provide a novel drawer-holding case, in the nature of a collapsible paper board box, which may be erected and held in stacked relation with similar cases in such manner, and by means such, that no paper board wall of any case is required to sustain the weight of any other case or its contents.

Another important object of the invention is to provide a novel drawer-holding case, in the nature of a collapsible paper board box, which is provided with novel means, some parts of which are permanently attached to the case and other parts of which are detachable accessories, for holding the case against "weaving," i. e., to prevent shifting movements of its walls which will distort its interior right angles.

A further object is to provide novel, simple and effective means for securing together adjacent cases stacked in side by side relationship.

Another object of the invention is to provide a drawer-holding case having the margins of its drawer receiving opening strengthened, and the opening held against distortion, by a novel arrangement of case-end flaps.

A further object is to provide novel liners for the cases to reduce the sliding friction of the drawers and reinforce the cases at points of greatest wear.

A further object is to provide novel stacking racks which are adapted to be connected with and lie between contiguous cases in a stack, which adequately support the floors or bottom walls of the several cases, and which may be employed to carry the lowermost case of a stack out of contact with the floor by which the stack is supported.

Still another object is to provide satisfactory drawers adapted to slide in and out of the cases.

These and other objects and advantages will become apparent during the course of the following description.

In the accompanying drawings, forming a part of this specification, and in which like numerals

are employed to designate like parts throughout the same:

Fig. 1 is a right front perspective view of a filing cabinet according to this invention;

Fig. 2 is an exploded perspective view of a case, liner and stacking rack;

Fig. 3 is an elevational view partly broken away of the rear end of one of the erected cases;

Fig. 4 is a right front perspective view of a partly erected case inverted to show the longitudinal edges thereof which are secured together by an adhesive tape, in the manufacture of the case;

Fig. 5 is a fractional front elevation, partly broken away, of a multiple stack filing cabinet of the present invention;

Fig. 6 is a sectional view taken in the direction of the arrows along the line 6-6 of Fig. 5;

Fig. 7 is a sectional view taken in the direction of the arrows along the line 7-7 of Fig. 6;

Fig. 8 is a sectional view taken in the direction of the arrows along the line 8-8 of Fig. 5;

Fig. 9 is a sectional view taken in the direction of the arrows along the line 9-9 of Fig. 2;

Figs. 10 and 11 are sectional views taken in the direction of the arrows along the lines 10-10 and 11-11 of Fig. 1, respectively;

Fig. 12 is a fractional front view of the lower left front corner of one of the cases showing the drawer in place;

Fig. 13 is a plan view of a blank from which a satisfactory drawer may be fabricated;

Fig. 14 is a right front perspective view of the drawer blank partially folded;

Fig. 15 is a right front perspective view of the drawer with the bottom liner exploded out of the other parts of the drawer;

Figs. 16 and 17 are sectional views of the drawer taken in the direction of the arrows along the lines 16-16 and 17-17 of Fig. 15 respectively.

Fig. 18 is a plan perspective view of a case cover.

In general, the filing cabinet consists of any convenient number of paper board filing case units, each one of which is shipped folded flat and erected by the user. When erected, these cases may be assembled into stacks which may consist of several vertical rows of cases, several tiers high, the whole being bound together into a solid unit by means of stacking racks, nuts and screws. At any time more units may be added to the top or at the side of any original stack.

When a plurality of cases are in stacked rela-

tionship, a metallic skeleton frame 28—S supports the load in each of the cases from the floor so that no load is carried by any of the paper board side walls 30. The said skeleton frame-work 28—S is a composite of two or more stacking racks 22 and the hereinafter described side wall stiles of the cases assembled with such stacking racks.

Each of the individual cases 20 consists of a rectangular paper board carton 32 of well known design in the manufacture of which a blank is cut and scored on a die and then folded and secured along its longitudinal edges 34 by means of an adhesive cloth strip 36. This case is provided on each of its vertical sides 30 with two stiles 38 and 40 which have a length equal to the height of the side walls 30. Each of these stiles 38 and 40, which are identical, consists of a metal channel strip 42 that is folded longitudinally back upon itself twice on each side of its center line, thereby providing two plane surfaces 44 with a substantially rectangular channel 46 between them. The channel 46 thus formed is covered for a short distance at each of its ends by a flat plate 48 spotwelded to the channel strip 42. The stiles 38 are secured as close as is practical to the front opening 50 of the case 20 by means of rivets 52 passing through the paper board, while the other stiles 40 are similarly secured somewhat from the rear end 54 of the case. The rivets 52 may be provided with washers 56 to resist the tendency of their heads to pull through the paper board.

The center of each of the stiles is provided with a slotted hole 58 which may be used in securing together adjacent cases in the same horizontal plane in a manner to be described. Behind each of these slotted holes 58 the container wall 30 is cut away as at 60 to give access to the insides of the stiles 38 and 40.

The above described case 20 is shipped flat. When received by the user, it is opened and the four rear flaps 62 turned to the position shown in Fig. 2 and then held by a gummed cloth strip 64 which, in the manufacture of the case, preferably has one end secured to one of the side walls 30. When the case is erected such strip 64 is adhesive applied to the outer ones of flaps 62 and the other side wall 30. The lower front flap 66 is then folded in and secured by a liner 68. The liner consists of a flat piece of paper board that is scored twice lengthwise, so that when folded along the scores it becomes a U-shaped member that fits inside the container 20 thus serving to protect the container from the wear produced by a sliding drawer 10. The horizontal portion of this liner has two embossed tracks 72 on which the drawer 10 slides. The front portions of the lower corners of the liner are notched at 74, along the score lines, rearwardly for distances slightly greater than the horizontal dimensions of the front side flaps 76.

After the front lower flap 66 has been folded inwardly and the liner 68 pushed into place, the two side flaps 76 are then folded in over the liner 68, in which positions their lower edges 78 will be caught in the notches 74. The top flap 66 is then similarly folded to place inside the case. It will be seen that the side flaps 76 retain the liner 68 against outward movement.

The inner ply of the card board, of which the liner 68 is formed, is preferably a sheet of paraffin paper. However, if the liner is formed of conventional card board its inner surfaces are smeared or coated with paraffin. The presence

of the paraffin, in either case insures that the opposed rubbing surfaces of the drawer and liner quickly become polished and slide very easily on and with respect to each other.

The cases 20 are secured in vertical stacks by means of the hereinbefore mentioned stacking racks 22. These racks, which may be constructed of strips 82 of machine steel welded together, are as wide as the container 20 and as long as the distance between the front and rear stiles 38 and 40. The stacking racks are braced against distortion by corner strips 84. The front and rear members of each rack 22 are continued beyond the corner welds and bent upwardly at right angles, thereby providing four upwardly projecting fingers 86 which may be slid into the openings 46 in the ends of the stiles 38 and 40 of an erected case. The lower surface of the frame 22 has welded thereto at its corners four L-shaped pieces 88 which provide downwardly extending fingers 90 similar to the fingers 86.

When stacking the cases, rubber cushions 92 are slipped over the downwardly projecting fingers 90 of a frame 22, and the frame placed on the floor. Then the lower ends of the stiles 38 and 40 of a container 20 are slipped over the upwardly projecting fingers 86 of the frame 22. Then the downwardly projecting fingers 90 of a second frame are slid into the openings 46 at the tops of the stiles 38 and 40, and so on until the stack 30 has reached the desired height.

To strengthen the uppermost case in a stack, a stacking rack 22, either with or without the upwardly projecting fingers 86, may be secured in place with its fingers 90 engaging the upper openings of the case stiles 38 and 40. However, a better appearance is given to the stack and a smooth writing or working surface is provided, if the top most case is strengthened by means of a sheet metal cover plate 93 having depending fingers 90 which engage the stiles 38 and 40. These fingers 90 can either be formed as shown in Fig. 18 by bending down edge portions of the plate 93, or they may be separate angle pieces welded to the plate 93 in the same manner that the pieces 88 are welded to the racks 22.

Although I have illustrated and described the stiles 38 and 40 as providing the female members, and the fingers 86 as being the male members in the interlocking mechanism, it readily will be understood by anyone skilled in the art that the stiles may be solid and the fingers hollow and fitted thereto, without departing from this invention.

If desired a second stack may be built alongside the first and horizontally adjacent cases secured together by means of nuts 24 and screws 26 passed through the slots 58 in the stiles 38 and 40 before the liners 68 are put in place. Since, when more than one stack is built the adjacent rubber cushions 92 at the bottom of the several stacks may interfere with each other, I prefer to use one rubber cushion 92 to enclose each set of two adjacent fingers 90 as shown in Fig. 11. It will be seen that filing cabinets when constructed in accordance with this invention will be very strong and rigid even though built largely of paper board sections, and that the weight in each drawer 10 will be transferred to the steel frames 22 beneath the cases 20, and from there to the stiles 38 and 40 which carry the load to the floor without reliance on the strength of the paperboard walls 30 of the cases lower down in the stack.

The drawers 10 to be used in connection with the above described cases may be of the construc-

tion shown in Figs. 13 to 17, inclusive. Such drawer is made from paper board and has a double thickness bottom and side walls and four thicknesses in the front and rear panels.

5. This drawer consists of a flat sheet 94 scored and cut to form a rectangular bottom 96 in the center of the blank with end walls 98 and end wall extensions 100 at either end, and side walls 102 and side wall extensions 104 at either side 10 of the bottom section 96. The side walls 102 and side wall extensions 104 are provided with outwardly extending flaps 106 at their ends, so that when the side walls 102 are folded into a vertical position with the side wall extensions 104 folded 15 down inside the drawer 70, the flaps 106 may be folded across the ends of the drawer and enclosed between the end walls 98 and the end wall extensions 100, which are folded in a manner similar to the side walls 102. In this position 20 eight holes 108 in the side flaps are brought into alignment with eight holes 110 in the end flaps and the drawer 70 secured in erected position by means of nuts 112 and screws 114 passed through these holes 108 and 110. The screws 114 passing 25 through the front wall are provided with washers 116 under their heads and serve to secure a handle 118 to the front of the drawer 70 as well as to hold the drawer in erected position. To strengthen the bottom of the drawer 70, I prefer 30 to add to the above a rectangular piece of paper board 120 cut to proper size which is inserted into the drawer and pressed against the bottom 96. This false bottom 120 also serves to press the side wall extensions 104 tightly against the side walls 102 and thereby provides a square corner between 35 the bottom of the drawer and the side walls.

Although I have described a preferred embodiment of my invention, it should be understood that I contemplate that departures may be made 40 therefrom, and that the scope of my invention is to be limited solely by the following claims.

I claim:

1. In a filing cabinet, a stack of drawer-receiving cases, each case comprising a collapsible paper board receptacle having top, bottom and side walls, a plurality of vertically disposed stiles mounted on and secured to the outer surfaces of the side walls of each case, and racks disposed between contiguous cases of the stack, each rack 45 comprising a horizontal frame adapted to underlie and support the bottom wall of a case directly above it, each such frame being provided with members arranged to have detachable load-transmitting connection with the stiles of the 50 cases above and below it, said racks and said stiles constituting a composite skeleton frame in and on which each case is so supported that its load is transmitted through the stiles of the underlying cases and the load-transmitting connections to the floor.

2. A file drawer case comprising in combination, a paper board container provided at its drawer entrance with a bottom flap and side

flaps, a U-shaped liner for the container, the liner serving to hold said bottom flap in place against the floor of the container, said side flaps serving to prevent movement of the liner outwardly through the drawer entrance, and longitudinal ridges upwardly embossed from the floor of the liner to aid sliding movements of a drawer in said case.

3. A filing cabinet comprising a plurality of collapsible paper board drawer cases arranged 10 in a vertical stack, each of said cases having bottom, top and side walls, a pair of spaced-apart hollow vertically disposed metallic stiles secured to the outer surface of each side wall of each case and not extending either above or below 15 such side wall, all of said stiles being adapted to become detachably associated with the hereinafter described racks to constitute a self-sustaining composite skeleton frame, and a plurality of horizontally disposed rectangular racks, 20 each rack lying immediately under one of the cases of the stack, the rack which lies immediately under the lowermost case having its corners in load-receiving relation to the lower ends of the stiles of such lowermost case and being 25 provided, at such corners, with upwardly projecting fingers which enter the lower ends of the stiles of such lowermost case, each of the other racks having its corners in load-receiving relation to the lower ends of the stiles of the case 30 immediately above and in load-transmitting relation to the upper ends of the stiles of the case immediately below, each of such last mentioned racks being provided at its corners with upwardly and downwardly extending fingers projecting into 35 adjacent vertically aligned hollow stiles.

4. A filing cabinet comprising a plurality of collapsible paper board drawer cases arranged in a vertical stack, each of said cases having bottom, top and side walls, a pair of spaced-apart 40 vertically disposed metallic stiles secured to the outer surface of each side wall of each case, all of said stiles being adapted to become associated with the hereinafter described racks to constitute a self-sustaining composite skeleton frame, and a plurality of horizontally disposed rectangular racks, each rack lying immediately under one of the cases of the stack, the rack which lies immediately under the lowermost case having its corners in load-receiving relation to the stiles of 45 such lowermost case and being provided, at such corners, with means for detachable connection with the lower ends of the stiles of such lowermost case, each of the other racks having its corners in load-receiving relation to the lower ends 50 of the stiles of the case immediately above and in load-transmitting relation to the upper ends of the stiles of the case immediately below, each of such last mentioned racks being provided at its 55 corners with means for detachable connection with contiguous stiles.

HARRY L. FELLOWES.
